UNITED STATES PATENT OFFICE.

ADOLPH H. WAGNER, OF MILWAUKEE, WISCONSIN.

SPLIT PULLEY.

SPECIFICATION forming part of Letters Patent No. 390,102, dated September 25, 1888.

Application filed February 3, 1888. Serial No. 262,897. (No model.)

To all whom it may concern:

Be it known that I, ADOLPH H. WAGNER, of Milwaukee, in the county of Milwaukee, and in the State of Wisconsin, have invented 5 certain new and useful Improvements in Split Pulleys; and I do hereby declare that the following is a full, clear, and exact description thereof.

My invention relates to split pulleys; and it 10 consists in certain peculiarities of construction and combination of parts, to be hereinafter described with reference to the accompanying drawings, and subsequently claimed.

In the drawings, Figure 1 represents a side 15 elevation of a pulley constructed according to my invention and partly broken away on line 1 1, Fig. 2; Fig. 2, a face view of the pulley, partly in section, on line 2 2, Fig. 1, and Fig. 3 a transverse section on line 3 3, Fig. 1. Figs. 20 4 and 5 are detail views of the meeting edges of the pulley-sections.

The rim of the pulley is made in the usual manner and then cut in two to form sections A B, the sides of said rim being finished with 25 a bead, C, that hides the cuts and increases the width of face. Half-round recesses E are cut in the meeting ends of the rim sections, and when these sections are together said recesses form circular openings for dowel-pins F, the 30 latter being shown as permanently secured by transverse pins or nails P, as shown in Figs. 1, 2, and 5, in the recesses of the rim section B.

While I have shown the half-round recesses E and circular pins F, it is obvious that said 35 recesses and pins may be angular, if found more desirable, the purpose of the pins being to prevent lateral displacement of the sections A B that form the rim of the pulley.

Mortised in each rim-section of the pulley 40 are the ends of a transverse brace-piece, G, said rim-section and brace-piece being keyed together by dowel-pins H that are shown as circular, but which may be of any other desirable form.

Passed through the brace-pieces of the opposing pulley-sections are rods I, and on the ends 45 of these rods are arranged clamping-nuts J.

Each of the brace-pieces G is centrally re-

cessed to engage a square hub, K, the latter being preferably made in two sections for the 50 sake of convenience, and held in place by the pressure of said brace-pieces. The hub K being detachable from the pulley, any-sized shaft can be accommodated without the employment of bushings, as it is only necessary to know 55 the diameter of said shaft in order to furnish a hub having a correspondingly-proportioned bore, it being intended that all hubs shall be of a standard size as regards outside measurement, and differ only as to the diameter of bore. 60

By the construction above described I provide a simple, easily constructed, and durable split pulley that has no liability to get out of shape or run loose on the shaft to which it may be connected. 65

I am aware that heretofore split pulleys have been made with removable hub-sections interposed between the arms thereof.

Having thus fully described my invention, what I claim as new, and desire to secure by 70 Letters Patent, is—

1. A split pulley having the meeting edges of its sections recessed, and dowel-pins fitted into the openings formed by the recesses and secured by transverse pins passing through 75 said dowel-pins and into one of said sections, substantially as set forth.

2. A split pulley having its rim-sections A B recessed at their meeting ends, dowel-pins fitted into the openings formed by the recesses 80 and secured by transverse pins passing through said dowel-pins and into one of said sections, the transverse brace pieces G, mortised and doweled in the rim-sections, the hub K, detachably fitted between the brace-pieces, the 85 rods I, and clamping-nuts J, substantially as set forth.

In testimony that I claim the foregoing I have hereunto set my hand, at Milwaukee, in the county of Milwaukee and State of Wisconsin, in the presence of two witnesses. 90

ADOLPH H. WAGNER.
